UNITED STATES PATENT OFFICE

ALEXANDER GUTSCHINNIKOFF, OF ARNSTADT, GERMANY

MULTIPLE-CARD MATCH PACKAGE

Application filed February 18, 1927, Serial No. 169,312, and in Germany February 18, 1926.

The present invention relates to improvements in matches, one object of the invention being the provision of a layer match in which the heads are staggered and are protected by a strip of paper or other material, said match being specially designed to be made or constructed by the machine as shown in my co-pending application filed February 21, 1927, Serial No. 169,311.

10 A further object of this invention is the provision of a package of matches in which layers can be folded accordion-like and each layer separated from the other by tearing the protecting strip for the heads thereof, thus 15 producing a very desirable type of match and one which can be easily carried without danger of accidental combustion.

In the accompanying drawings:

Figure 1 is a plan view of a portion of the 20 web after the protecting strip of paper has been attached thereto, the respective ends of the paper being torn away to show the position of the heads of the matches.

Figure 2 is a perspective view of the match 25 web folded accordion-like.

Referring to the drawings, a web of matches as constructed in the machine above referred to in my co-pending application is fed into the paper-applying machine so that 30 the two strips *a* of paper are properly folded to encase the heads without the adhesive carried portion thereof contacting the heads, the match or stick bodies being engaged beyond the heads, as clearly illustrated, and to form a 35 flat package *b*. The heads *c* of the two adjacent matches, as provided for in the machine, the subject-matter of the co-pending application, are in opposite directions so that the two strips of paper are necessary to protect the 40 same and at the same time it renders the easy adhesion of the inflammable material to the head during the process of manufacture. The paper is perforated at equidistant points as at *d* so that the strips can be folded 45 accordion-like, as shown in Figure 2, and thus short webs can be torn therefrom as the matches are used, the paper strips, in addition to acting as a protector for the heads, at the same time act as a means for holding the various layers or packages of the matches to-

gether in their relative position so that all that is necessary to be done in using the matches is to tear the paper at both sides so as to release one or two matches at a time.

It will be apparent from the foregoing that 55 the present match package can be made in short strips or in the accordion-like construction, as illustrated in Figure 1, and that the alternate or zig-zag located heads thereof will be protected at all times by the paper strips 60 43, thus rendering each match readily accessible for use.

I claim:

1. A package of matches consisting of a 65 plurality of layers, each layer of which has the heads of its matches disposed in zig-zag order throughout the length of the layer, and two strips of protecting material for the heads of said matches enclosing the heads and attached to the bodies of the matches beyond 70 the heads.

2. A package of matches consisting of a 75 plurality of layers, each layer of which has the heads of its matches disposed in zig-zag order throughout the length of the layer, and two strips of protecting material for the heads of said matches enclosing the heads and attached to the bodies of the matches beyond the heads, said strips also acting as a means to hold the matches relatively one to the other.

3. A package of matches composed of a 80 plurality of continuous strips of matches, the ends of which are covered by a flexible tearable material to permit the strips to be folded accordion-like.

4. A package of matches composed of a 85 plurality of continuous strips of matches, the heads of which are covered by a flexible tearable material to permit the strips to be folded accordion-like, said flexible material being perforated at each fold to permit separation of the strip at such points and to permit the folding of the strips one upon the other.

5. A layer of matches, the heads of which 95 are alternately disposed at opposite ends and two flexible strips of tearable material enclosing the heads at each end of the layer to form a protecting means for the heads, said strips being carried bodily by the layer.

6. A layer of matches, the heads of which 100

are alternately disposed at opposite ends and two flexible strips of tearable material enclosing the heads at each end of the layer to form a protecting means for the heads, said strips being carried bodily by the layer, and the matches being held relatively to each other by said strips.

7. A layer of matches, the heads of which are alternately disposed at opposite ends and two flexible strips of paper enclosing the heads at each end of the layer to form a protecting means for the heads, said strips being carried bodily by the layer.

10 In testimony whereof I have hereunto set my hand.

15 ALEXANDER OVTSCHINNIKOFF.
